FIGURE 1 is a perspective view of a ladder display stand showing my new design;

FIGURE 2 is an elevational view taken from one end thereof;

FIGURE 3 is an enlarged fragmentary view of the horizontal positioned end brace;

FIGURE 4 is a cross sectional view taken on line 4-4 of FIGURE 3;

FIGURE 5 is a cross sectional view taken on line 5-5 of FIGURE 1;

FIGURE 6 is an elevational view taken from the end opposite that shown in FIGURE 2;

FIGURE 7 is a top plan view thereof;

FIGURE 8 is a fragmentary view of a portion of one of the angled end uprights;

FIGURE 9 is a cross sectional view taken on line 9-9 of FIGURE 8;

FIGURE 10 is a fragmentary elevational view of the upright shown in FIGURE 8;

FIGURE 11 is a fragmentary top plan view of the cross bar; and

FIGURE 12 is a cross sectional view taken on line 12-12 of FIGURE 11.

The dominant features of my design reside in the portions shown in full lines, it being understood that the broken line representation of a step ladder and an extension ladder in FIGURE 6 is for purposes of illustration only.

I claim:

The ornamental design for a ladder display stand, as shown and described.
